UNITED STATES PATENT OFFICE.

GEORGE W. BERRY, OF LORNA DOONE, NEW SOUTH WALES, AUSTRALIA.

OPENER AND CLOSURE FOR CANS.

1,271,533.

Specification of Letters Patent.

Patented July 9, 1918.

Application filed August 11, 1917. Serial No. 185,637.

To all whom it may concern:

Be it known that I, GEORGE WILLIAM BERRY, a subject of the King of England, and a resident of Lorna Doone, Old South 5 Head Road, Rose Bay, in the State of New South Wales, Commonwealth of Australia, have invented certain new and useful Improvements in Openers and Closures for Cans, of which the following is a specification.

This invention relates to removable closures or covers for circular cans to be utilized in connection with cans hermetically sealed with one end closure of the can 15 comprising taggers tin, said cover consisting of a disk portion having an annular flange provided with an integral cutter or cutter nib which is adapted to pierce and cut or rip the taggers tin closure of the can.

20 In one form of closure of this character the cutter is stamped from the material of the disk portion of the closure to extend in a plane substantially parallel with said disk portion in the normal inoperative position 25 or use of the closure and to lie contiguous to the taggers tin closure of the can when the cover is applied to such can, and to use the cutter it is necessary to bend the cutter to extend substantially parallel with the flange

30 of the closure. In other closures of this type the cutter as it is stamped from the closure is bent to extend vertically or parallel to the closure flange necessitating means to retain the closure in its inoperative position on 35 the can so that the cutter will not contact with the taggers tin end of the can. In both instances after the taggers tin end of the can is removed and the removable cover is utilized to close such end of the can the

40 contents of the can are always open to the atmosphere through the opening from which the cutter is stamped with the consequent deterioration of the contents of the can.

In another form of closure of this character 45 the cutter is made separate from the closure and movably secured thereto thereby greatly increasing the cost of manufacture. In the normal inoperative position of this type of closure when applied to 50 the can the cutter lies contiguous to the inner face of the closure flange and the can body with the result that it is necessary to make the flange of the closure larger than the can body and consequently to fit 55 loosely thereon.

It is the object of the present invention

to overcome the above disadvantages and to provide a closure of this character with improved cutting means integral therewith, whereby the disk portion of the closure will 60 at all times lie contiguous to the end of the can and the closure flange will snugly fit the sides both before and after the taggers tin end of the can has been removed.

In the drawing accompanying and forming 65 a part of this specification Figure 1 is a side elevation of a can with a removable closure showing an embodiment of my improved cutting means and the closure in its normal inoperative position on the can.

Fig. 2 is a side elevation of the closure.

Fig. 3 is an enlarged sectional view of a portion of the closure taken on the line 3—3 of Fig. 2, showing the normal position of the cutting means.

Fig. 4 is an enlarged sectional view of a portion of the can and the closure applied thereto, the section being taken substantially on the line 4—4 of Fig. 1 and showing the position of the cutting means in the normal 80 inoperative position of the closure.

Fig. 5 is a view similar to Fig. 4 but showing the cutter as piercing the taggers tin end of the can and in operative cutting position; and

Fig. 6 is a sectional view of a portion of a can after the taggers tin end has been removed, and showing the edge of the taggers tin closure at which said closure was severed turned over or pressed smoothly to the 90 inner surface of the can body during the cutting operation.

Similar characters of reference designate like parts throughout the different views of the drawing.

In the drawing I have shown an embodiment of my invention in connection with a can having a round or circular body 7, said body either being drawn up from a blank with one end or the bottom integral with the 100 body, or such end may be secured thereto by a seam or soldering, or both. After the material which is to be carried in the can is placed therein, the other end or top is closed and hermetically sealed by a taggers tin 105 closure 9, a portion of such closure as usual lapping around the side of the can, as at 10, and soldered thereto.

My improved closure comprises a disk 11 having an annular flange 12 extending substantially at right angles to the disk portion, and the latter portion may be slightly

depressed with relation to the juncture thereof with the flange, as shown at 13. A portion of the closure flange is stamped therefrom to provide walls 14 extending 5 from the base of the closure flange to adjacent the disk portion 11 and a depending V-shaped nib 15 to constitute the cutter and being preferably of slightly less length than the closure flange. Between the cutter nib 10 at the base thereof and the walls 14 there is a blank space substantially as shown at 16 for a purpose to be hereinafter described. The cutter nib 15 is bent inward slightly from the closure flange and provided with a 15 shoulder 17 at the juncture of the nib with the closure flange, this shoulder not only strengthens the cutter nib but also increases the inherent resiliency or springiness of the nib. In applying the closure to 20 the can so that the cutter nib will not pierce the taggers tin end of the can the closure or lid is slightly tilted as shown in dotted lines in Fig. 4 to cause the cutter nib to embrace the outside of the can body, when the 25 side of the closure opposite to the cutter nib is pushed onto the can until the disk portion is contiguous to the taggers tin end of the can, which may be readily done as the cutter nib will slightly spring or give due 30 to the inherent resiliency of the material thereof, and thereby eliminating any possibility of the cutter nib piercing the taggers tin end. Furthermore, this inherent resiliency of the material of the cutter nib 35 serves to firmly retain the closure on the can and prevents the accidental displacement of the same.

To cut or sever the taggers tin end of the can the cover is removed from the can when 40 the cutter nib will spring slightly inward to its initial position shown in Fig. 3. The closure is then applied so that the entire circumference of the closure or cover flange will embrace the outside of the can body, 45 in which position the V point or apex of the cutter nib will engage the taggers tin end in a line just within and close to the can body, when the closure is forced onto the can and the cutter penetrates into the 50 taggers tin end until the shoulder 17 at the juncture of the cutter nib and the closure flange engages the top edge of the can body, as shown in Fig. 5. By rotating the closure in this position the cutter nib will rip or

sever the taggers tin end secured to the 55 can, and during such rotary movement of the closure the pressure of the shoulder 17 against the edge of the taggers tin end secured to the can will turn over this edge and press it smoothly against the inner face of 60 the can body thereby obviating any possibility of injury to the hand in removing the contents of the can.

Having thus described my invention, I 65 claim:

1. In combination with a can, of a closure therefor having a depending flange, said flange having a downwardly pointed cutter nib cut and set inwardly therefrom to provide a shoulder whereby, when the 70 closure is applied to the can with the cutter nib sprung outwardly to engage the outer face of the can, said shoulder will frictionally engage the can and serve as a lock for the closure. 75

2. A can closure having a flange to extend in a direction longitudinally of the can body with portions cut therefrom and through the edge of the flange to form a depending V-shaped cutter nib integral with 80 the closure flange, and said nib being bent inward to form a shoulder at the juncture of said nib with the closure flange and adapt the nib to normally extend yieldingly inward from the flange, said nib being adapted 85 to lie contiguous to the outer face of the can body in the normal inoperative position of the closure on the can, or adapted to pierce a taggers tin end of the can and lie contiguous to the inner face of the can body 90 with the shoulder at the juncture of the nib and closure flange engaging with the edge of the can body and operate to press the severed edge smoothly against the can body as the end of the can is severed, substantially 95 as and for the purpose specified.

3. In combination with a can, having a peripheral bead about its top portion, of a closure therefor having a depending flange, said flange having a downwardly pointed 100 cutter nib cut and set inwardly therefrom to provide a shoulder whereby, when the closure is applied to the can with the cutter nib sprung outwardly to engage the outer face of the can, said shoulder will 105 frictionally engage beneath the bead of the can and serve as a lock for the closure.

G. W. BERRY.
